UNITED STATES PATENT OFFICE.

THOMAS A. BREWER, OF LOUISVILLE, KENTUCKY.

PERFORATOR ATTACHMENT FOR PRINTING-PRESSES.

1,254,973.

Specification of Letters Patent. Patented Jan. 29, 1918.

Application filed November 18, 1918. Serial No. 132,214.

To all whom it may concern:

Be it known that I, THOMAS A. BREWER, a citizen of the United States, residing at Louisville, in the county of Jefferson and State of Kentucky, have invented new and useful Improvements in Perforator Attachments for Printing-Presses, of which the following is a specification.

This invention relates to a perforator attachment for printing presses, the object of the invention being to provide a perforator which may be readily and conveniently applied to the gripper fingers of a Gordon type of press for use, and which will operate in a reliable and efficient manner to perforate the stock.

A further object of the invention is to provide a perforator including supporting means which may be employed for holding perforating devices or blades of any size and at any point in the length of the grippers.

A still further object of the invention is to provide a perforator embodying means for reliably withdrawing the perforating blade from the stock after an impression is made.

A still further object of the invention is to provide means for supporting the perforator blade in either a horizontal or vertical position.

The invention consists of the features of construction, combination and arrangement of parts hereinafter fully described and claimed, reference being had to the accompanying drawing in which:—

Figure 1 is a front elevation showing the application of the invention to a pair of grippers.

Fig. 2 is a longitudinal section through the main supporting bar and parts shown in Fig. 1.

Figs. 3, 4 and 5 are vertical transverse sections on lines 3—3, 4—4 and 5—5 of Fig. 1, Fig. 4 showing in full and dotted lines the normal and projected positions of the perforating blade.

Fig. 6 is a perspective view of an auxiliary supporting bar for supporting the blade in a vertical position.

In carrying my invention into practice I

provide a device of the character described comprising a main supporting bar 1 adapted to extend horizontally between the grippers 2 of the printing press and provided with back-turned ends 3 forming cuffs or clips to slidably engage the grippers, each of said cuffs or clips being provided with a set screw 4, whereby the bar may be disposed at any point in the length of the grippers to extend across the face of the platen when the parts of the press are disposed in position for an impression.

The bar 1 is provided upon one of its faces with a longitudinally extending dovetailed guideway 5 which terminates at its end, short of the cuffs 3, leaving intervening entrance ways or passages 6. A narrow slot 7 permits the perforating plate 11 to project through the side of the bar opposite the platen. The entrance portion of the guideway 5 which is narrower than the base portion thereof is designated 8.

The bar 1 is adapted to support the carrier bar 9 which is adapted to fit within the guideway and is provided in its rear side with a longitudinally extending slit or recess 10 to the back edge of a perforator 11 which may be provided at its forward edge with perforated teeth or projections 13, screws or other similar fastenings 13' being provided upon the bar 9 for engagement with the blade to detachably hold the same in position. It is of course to be understood that the bar 9 is adapted for receiving and holding perforator blades of different lengths, as may be required in the case of the perforator.

The ends of the bar 9 are provided with tongues or reduced portions 14 to fit within sockets 15 in a pair of holding blocks 16 provided with dove-tailed lugs or projections 17 to slidably engage the dove-tailed guideway 5, which blocks are adapted to be inserted and removed through the entrance-way 6 and to be held in position by means of the lugs 17 and suitable fastening members 18. These fastening members 18 are in the form of hooks or fingers adapted to engage over one of the longitudinal edges 100 of the bar 1 and are secured thereto by set screws 19 whereby the blocks will be held

in position to support the bar 9 and blade 11 against displacement.

When the bar 9 is disposed upon the grippers in position for use the side thereof provided with the slot 7 is arranged to face the formed bed of the press, while the opposite side thereof is arranged to face the platen, so that the bar 9 will be disposed for contact with the formed bed and the edge 12 of the blade 11 will extend through the slot 7 for engagement with the paper or stock upon the platen at the moment of impression.

The ends 14 of the bar 9 which fit within the sockets 15 of the hollow block 16 are arranged to bear against backing springs 20, which springs are disposed to retain said bar and the perforator blade in normal or retracted position while permitting the same to be forced forward for impression by contact of the bar 9 with the formed bed of the press, the springs serving subsequently to return said parts to normal position after the impression is made.

It will thus be understood that after a perforator blade of the required length has been applied and placed in the desired position for use, the movement of the parts of the press for the impression action will bring the bar 9 in contact with the formed bed and force the same rearwardly toward the platen against the resistance of the springs 20 at the moment of impression, thus projecting the perforating edge of the blade rearwardly to engage the stock upon the platen, and at the moment of impression, whereby when the parts of the press move away from each other after the impression is made, the springs 20 in reacting return the bar 9 and blade 11 to normal position, and in so doing withdraw the blade from engagement with the paper, for a positive separating action in the event that there should be any tendency of the teeth of the blade to stick or hang in the paper stock. It will be understood, of course, that the bar 1 may be disposed at any elevation upon the grippers, and that one or more bars with the perforating attachments may be employed for making a series of perforated lines, if desired.

I also provide a means for supporting a perforated attachment consisting of the bar 9^a and blade 10 with a vertical position, such means consisting of an auxiliary supporting bar 21 having a dove-tail guideway 5^a, entrance-way 6^a, at at least one end thereof, slot 7^a, in which respects the bar 21 is similar in construction to the bar 1, but said bar 21 is provided at one end with means for engaging the bar 1 comprising a dove-tailed lug 22 to fit within the guideway 5 and a retaining hook or finger 23 to engage over one of the longitudinal edges

of the bar 4, said fingers being provided with a clamping screw 24 to secure it in position. This bar 21 may thus be slidably fitted upon the bar 1 to dispose it in any vertical position between the grippers and is adapted to receive the bar 9 and blade 11 and the holding blocks 16 in the same manner as that previously described with reference to the bar 1, so that the perforator blade may be disposed in a vertical position for use.

It will, of course, be understood that one or more of these bars 21 may be applied to the bar 1 to hold a corresponding number of perforator blades as may be required in use.

I claim:—

1. A perforator attachment for printing presses comprising a supporting bar having means of attachment to the press grippers, said bar being provided with a dove-tailed guideway opening toward one side of the bar, and said bar having a slot in the opposite side thereof communicating with the guideway, a carrier bar, a perforator blade carried by said bar and adapted to project through the slot, and holders provided with dove-tailed members engaging the dove-tailed guideway of the supporting bar and means for resiliently mounting the carrier bar in the holders.

2. A perforator attachment for printing presses comprising a supporting bar adapted for attachment to the press grippers, said bar being provided with a longitudinal guideway, opening toward one side of the bar, and said bar having a slot in the opposite side thereof communicating with the guideway, a carrier bar, a perforator blade carried by the carrier bar and adapted to project through the slot, and holding members engageable with the guideway in the supporting bar and provided with means of attachment to said bar, said holding members having sockets to receive the ends of the carrier bar and springs in said sockets arranged to permit the carrier bar and blade to be moved in one direction for making an impression and serving to return said bar and blade to normal position after the impression is made.

3. A perforator attachment for printing presses comprising a main supporting bar adapted to extend horizontally between and to be secured to a pair of grippers, said bar being provided with a longitudinal guideway opening toward one side of the bar, and said bar having a slot in the opposite side thereof communicating with the guideway, a carrier bar, and a perforator blade carried by the carrier bar and adapted to project through the slot, and holding members adapted to fit within the guideway and provided with means of attachment to the sup-

porting bar and adapted to engage and hold the carrier bar, and an auxiliary supporting bar provided with a guideway and slots similar to the main supporting bar to receive and support a carrier bar, blade and holding members, and provided at one end with a projection to engage the guideway in

the main supporting bar and with means for fastening it thereto, whereby the carrier bar and blade last named may be supported 10 from the main supporting bar in a vertical position.

In testimony whereof I affix my signature.
THOMAS A. BREWER.
